United States Patent Office

Des. 184,893
Patented Apr. 14, 1959

184,893

SPRINKLING CAN

Jean O. Reinecke, Oak Park, Ill., assignor to Federal Tool Corporation, Chicago, Ill., a corporation of Illinois

Application March 14, 1958, Serial No. 50,029

Term of patent 14 years

(Cl. D58—17)

FIG. 2

Fig. 1 is a side elevational view of a sprinkling can embodying my new design;

Fig. 2 is a top plan view thereof; and

Fig. 3 is a rear elevational view thereof.

I claim:

The ornamental design for a sprinkling can, substantially as shown.
